CAR DOOR

Kenneth J. Tobin, Chicago, Ill., assignor by
mesne assignments, to The Youngstown Steel
Door Company, Cleveland, Ohio, a corporation
of Ohio

Application November 12, 1934, Serial No. 752,638

12 Claims. (Cl. 20—22)

This invention relates to doors for railway cars and is directed particularly to doors for stock cars.

It is among the objects of this invention to provide doors for stock cars which shall be considerably lighter in weight than the present known doors, simpler and sturdier in construction, less expensive and easier of operation; doors which shall require less space for storage; in which running repairs may be made—that is, without withdrawing the car from service; wherein repairs can be made while the door is still on the car; doors which shall eliminate a substantial amount of the fixtures now required; doors for stock cars which shall decrease the possibility of damage to the stock; and which shall reduce the cost of maintenance.

With these expressed and other objects in view, which shall become clear as the description proceeds, this invention comprises the novel structure and combination of parts hereinafter described and more particularly pointed out and defined in the appended claims.

In the drawings forming part of this specification

Figure 1 is a fragmentary elevation of one embodiment of the invention;

Figure 2 is a vertical section taken on line 2—2 of Figure 1;

Figure 3 is a horizontal section taken on line 3—3 of Figure 1;

Figure 4 is an enlarged elevation of the lower right hand corner of the structure shown in Figure 1;

Figure 5 is a fragmentary elevation of another embodiment of the invention;

Figure 6 is a fragmentary elevation, showing the structure of Figure 5 as applied to a double deck stock car;

Figure 7 is a partial horizontal section taken on line 7—7 of Figure 5;

Figure 8 is a horizontal section taken on line 8—8 of Figure 5;

Figure 9 is a vertical section taken on line 9—9 of Figure 5; and

Figure 10 is a vertical section taken on line 10—10 of Figure 6.

Referring to the embodiment of the invention illustrated in Figures 1 to 4, inclusive, of the drawings the numeral 10 designates the side of a railway house car, illustrated as a stock car, and embodying a side plate 11, a side sill 12 upon which the floor 13 is supported, front and rear door posts 14 and 15, spaced siding members 16

and side braces, one of which is indicated at 17. The side plate, side sill and front and rear door posts define an opening 18 in the car side, which opening is adapted to be closed by a door 19 of the instant invention.

The door 19 of the considered embodiment of the invention comprises a plurality of spaced vertical flexible members 20, the upper ends of which are secured to the depending leg 21 of the side plate. The door 19 embodies, additionally, a plurality of flexible horizontally spaced members 22 secured to the vertical members 20 at their points of intersection. As indicated above, the members 20 and 22 are flexible and for this purpose it is proposed to utilize chains in their construction, as clearly illustrated in the drawings. The spacing of the horizontal members 22 in the lower zone of the door is relatively close. In the intermediate zone of the door this spacing is preferably increased, while in the upper zone of the door a further increase in the spacing may be resorted to. The closeness of the spacing in the lower zone of the door is desirable for the prevention of injury to livestock inasmuch as it prevents the livestock from accidentally sticking their limbs through the spaces between the horizontal members. In the higher zones of the door this problem does not exist and, consequently, the spacing may be increased.

The door 19 is adapted to be moved vertically in order to expose the door opening for the loading and unloading of livestock. To obtain such movement of the door a guide 23 is secured to the car 10 adjacent the forward edge of the door opening and a guide 24 is secured to the car adjacent the rear edge of the door opening. These guides, as clearly shown in Figure 3 of the drawings, are preferably channel-shaped in section and are disposed with their webs in abutment with the front and rear door posts so as to present flanges 25 and 26 disposed in spaced parallel relationship to the car side. Slidably engaged with the flanges 25 and 26 of the guides are a plurality of hook-shaped guide members 27 and 28 secured, respectively, to the forward and rear ends of each of the horizontal members 22 of the door. Vertical movement upwardly in the instant embodiment of the invention may be had by means of a plurality of cables 29, 30 and 31. The cable 29 extends through eyes 32 provided in each of the guide members 27 and the end thereof is secured to the lowermost of these guide members. The cable 29 passes over a pulley 33 secured to the side plate 11 and is then directed rearwardly over pulley 34, around pulley 35 and

thence downwardly to a drum 36 secured upon the car side.

The cable 38 is secured to the eye of a collar 37 fastened to a bar 38 hereinafter referred to. 5 From this fastening the cable 38 extends upwardly and around pulley 39 from whence it is directed rearwardly over a pulley and thence downwardly to the winding drum 36.

The cable 38 extends through eyes 40 provided in the rear guide members 23 and is fastened to the lowermost of such guide members. From its point of fastening the cable 38 extends upwardly and around pulley 41 and then downwardly to the winding drum 36.

15 The drum 36 is adapted to be rotated by means of a crank 42 fastened to the drum, said crank being provided with a pivotally secured handle 43. The handle 43, when in extended position as shown in Figure 1 of the drawings, is adapted 20 to lie between the flange 44 of stop member 45 and the side of the car. In the elevating movement of the door the crank 42 is moved clockwise until the handle 43 is disengaged from the stop member 45, whereupon said handle is swung 25 outwardly until it extends at a right angle to the remainder of the crank member, whereupon continued clockwise movement may be imparted to the winding drum 36 without interference from the stop member. The door may be maintained in elevated position by disposing the handle 43 behind the stop member.

Means is provided for tensioning and securing the door in its lowered or closed position. To this end there is secured to the side sill 12 by 35 means of an angle bar 46 a plurality of abutment members 47. The lower end of each of the vertical members 20 carries a detent member 48 provided with openings through which the bar 38 extends to insure simultaneous movement of 40 the detent members. The abutment members 47 are provided with depending arcuate portions 49 which are bifurcated as indicated at 50 in order to receive the detent members 48. In the locking and tensioning engagement between said detent and abutment members engagement is effected between the cam-shaped flanges 51 provided on the detent members and the arcuate portions of the abutment members.

To effect this engagement between said arcuate portions and said cam flanges there may be 50 utilized a bar 52 rotatably journaled in the guides 23 and 24. A plurality of fingers 53 and 54 are fastened upon the bar or shaft 52 so as to rotate therewith. An actuating member 55 is fastened to one end of the shaft 52, preferably 55 the rear end, as shown in Figure 1 of the drawings, for imparting rotation to said shaft. In the secured position of the door the actuating member 55 is disposed behind a pivoted catch 56, the free end of which is received behind a flange 57 provided on a bracket member 58 secured to the car. A seal (not shown) may be threaded through the flange 57 and a flange 59 provided on the catch 56. The door 19 may thus 60 be secured in its closed position against unauthorized opening thereof.

It will be apparent that when the door is to be elevated the seal (not shown) will be removed and the actuating member 55 released from the catch 56. The member 55 will then be rotated 70 downwardly and outwardly of the car so as to impart rotation to the shaft 52 and effect release of the fingers 53 and 54 from the bar 38. The detent members 48 may then readily be disengaged from the abutment members 47 where-

upon, by actuation of the winding drum 36, the door may be elevated. When the door has been lowered it may be tensioned and secured in lowered position by a reversal of the steps hereinabove set forth, it being apparent that as the 5 fingers 53 and 54 force the bar 38 inwardly toward the car the detent members 48 will pass into the bifurcations provided in the abutment members 47 and the engagement between the arcuate portions 49 of each of the abutment members and the cam flanges 51 of the detent members will tension the vertical members 20 of the door during the inward movement of the bar 38.

It will be apparent, moreover, in the elevating 15 movement of the door that the guide members 27 and 28 will slide upon the flanges 25 and 26 of the guides 23 and 24 and that the guide members 27 and 28 will successively engage the immediately higher guide members during this 20 movement of the door.

A further embodiment of the invention is illustrated in Figures 5 to 10, inclusive, of the drawings. This embodiment is shown in its application to a single deck stock car in Figures 5, 25 7, 8 and 9 and is illustrated in its application to a double deck stock car in Figures 6 and 10. Referring to Figure 5 of the drawings, this embodiment of the invention is found in a door 60 which comprises a plurality of spaced vertical members 61 and a plurality of spaced horizontal members 62 secured to the vertical members at their points of intersection. As in the previous embodiment of the invention, these members 61 and 62 preferably take the form of chains and the 30 spacing of the horizontal members 62 as described hereinabove is preferably maintained. The upper ends of each of the vertical members 61 are provided with guide members 63 adapted to slidably engage a guide 64 secured to the 35 depending leg 21 of the side plate 11. The lower ends of the vertical members 61 are provided with guide members 65 slidably associated with a guide 66 secured to the horizontal leg of the angle member 46.

The forward ends of the horizontal members 62 are secured to a vertical bar 67, the upper end of which is provided with a guide member 68 carrying a roller 69 having engagement with the guide 64. The lower end of the bar 67 is provided with a guide member 70 slidably associated with the guide 66 and provided with a roller 71 engageable with said guide 66 in the event of tilting of the bar 67 to prevent binding of said bar upon the guides 64 and 66.

The rear ends of the horizontal members 62 are fastened to the car side by securement to an angle member 72 which, in turn, may be bolted to the car side as indicated at 73. It will be apparent from Figure 9 of the drawings that by virtue of 60 the connection of the horizontal members 62 to the side of the car such members are inclined from substantially the rear door post to the car side. This inclination is maintained at the rear portions of the guides 64 and 66 as indicated at 65 74, whereby in the open position of the door 60 it will be disposed closely adjacent the car side.

In the movement of the door to open position the bar 67 will be grasped and slid along the guides 64 and 66. During this sliding movement 70 of the bar 67 it will successively contact the guide members 63 and 65 secured to the upper and lower ends of the vertical members 61 and cause the guide members to slide along the guides. As indicated hereinabove in the open position of the 75

door it will be stored compactly adjacent the car side.

As in the previous embodiment of this invention means is provided for tensioning and fastening the door in its closed position. To this end brackets such as 75 are fastened to the car side at the upper and lower portions thereof. These brackets provide bearings for a shaft 76 journaled therein. A plurality of brackets 77 are fastened upon the shaft 76, these brackets providing bearings in which a shaft 78 is journaled. A plurality of hook-shaped fingers 79 are fastened upon the shaft 78. The intermediate bracket 77 carries a pivotally secured actuating member 80 for imparting movement to the shaft 76 and through the brackets 77 fastened to said shaft movement is imparted to the shaft 78.

It will be clear from the foregoing that inasmuch as the shaft 78 may rotate within the bearings 77 the fingers 79 may be disposed in hooked engagement with the bar 67 of the door 60 when said door is brought to closed position. After this engagement is effected the actuating member 80 may be swung in a clockwise direction, as viewed in Figure 7 of the drawings, therewithal imparting clockwise rotation to the shaft 76 and similar rotation to the brackets 77 secured upon said shaft. This movement of the actuating member, consequently, will tend to move the bar 67 forwardly or toward the left, as viewed in Figure 7 of the drawings, and hence tension the horizontal member 62 of the door.

The actuating member 80 is preferably utilized in order to fasten the door in its closed position. For this purpose there is provided a lock member 81, carrying a vertically reciprocable pin 82. After the door has been properly fixed in its closed position the actuating member 80 will lie between the housings 83 and 84 carrying the pin 82, whereupon the pin may be extended through said housings and in front of the actuating member. A seal (not shown) may then be utilized to fasten the pin and the lock member 81 together.

The door illustrated in Figures 5, 7, 8 and 9 of the drawings is utilized as illustrated in Figures 6 and 10 of the drawings upon a double deck stock car. The floor of the upper deck of the car is indicated at 85. In a double deck stock car two doors are utilized, one for each of the decks. The construction of each of these doors is identical with that of the door 60, differing therefrom only in height. No further description of these doors is consequently thought to be necessary.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. In a stock car having a door opening, vertical guides secured adjacent to the vertical margins of said opening, a door for closing said opening, said door comprising a plurality of spaced vertical flexible members, a plurality of spaced horizontal members secured to said vertical members, members secured to the ends of said horizontal members slidably engaging said guides, means for securing the upper ends of said vertical members to said car, a bar secured to the lower ends of said vertical members, means en-

gageable with said bar for fastening said door and means for moving said door upwardly.

2. In a stock car having a door opening, vertical guides secured adjacent the vertical margins of said opening, a door for closing said opening, said door comprising a plurality of spaced vertical flexible members, a plurality of spaced horizontal members secured to said vertical members, members secured to the ends of said horizontal members slidably engaging said guides, means for securing the upper ends of said vertical members, detent members carried by the lower ends of said vertical members, abutments secured to said car below said door opening and means for effecting engagement between said detent members and said abutments for locking said door in closed position.

3. In a stock car having a door opening, vertical guides secured adjacent the vertical margins of said opening, a door for closing said opening, said door comprising a plurality of spaced vertical flexible members, a plurality of spaced horizontal members secured to said vertical members, members secured to the ends of said horizontal members slidably engaging said guides, means for securing the upper ends of said vertical members, a bar secured to the lower ends of said vertical members, detent members carried by said bar, abutments secured to said car below said door opening, a shaft rotatably journaled on said car, a plurality of fingers carried by said shaft and means for rotating said shaft, said fingers engaging and moving said bar to effect engagement between said detent members and said abutments to tension said vertical members.

4. In a railway car having a door opening, guides secured to said car above and below said opening, a door for closing said opening, said door comprising a plurality of spaced vertical members, a plurality of flexible spaced members secured to said vertical members and guide members secured to the ends of said vertical members slidably associated with said guides, said guides being inclined toward said car adjacent to and beyond the rear edge of said door opening.

5. In a railway car having a door opening, guides secured to said car above and below said opening, a door for closing said opening, said door comprising a plurality of spaced vertical members, a plurality of flexible spaced horizontal members secured to said vertical members, guide members secured to the ends of said vertical members slidably associated with said guides, and a vertical bar slidably associated with said guides, the ends of said horizontal members being secured to said vertical bar and said car adjacent to and beyond the rear edge of said door opening.

6. In a railway car having a door opening, guides secured to said car above and below said opening, a door for closing said opening, said door comprising a plurality of spaced vertical members, a plurality of flexible spaced horizontal members secured to said vertical members, guide members secured to the ends of said vertical members slidably associated with said guide, and a vertical bar slidably associated with said guides, the ends of said horizontal members being secured to said vertical bar and said car adjacent to and beyond the rear edge of said door opening, and means provided on said car side for engaging said vertical bar and tensioning said horizontal members in the closed position of said door.

7. In a railway car having a door opening,

guides secured to said car above and below said opening, a door for closing said opening, said door comprising a plurality of spaced flexible vertical members, a plurality of flexible spaced horizontal members secured to said vertical members, guide members secured to the ends of said vertical members slidably associated with said guides and a vertical bar slidably associated with said guides, the ends of said horizontal members being secured to said vertical bar and said car adjacent to and beyond the rear edge of said door opening.

8. In a railway car having a door opening, guides secured to said car above and below said opening, a door for closing said opening, said door comprising a plurality of spaced flexible vertical members, a plurality of flexible spaced horizontal members secured to said vertical members, guide members secured to the ends of said vertical members slidably associated with said guides and a vertical bar slidably associated with said guides, the ends of said horizontal members being secured to said vertical bar and said car adjacent to and beyond the rear edge of said door opening, and means for tensioning said horizontal members and fastening said door in closed position.

9. In a railway car having a door opening, guides secured to said car above and below said opening, a door for closing said opening, said door comprising a plurality of spaced flexible vertical members, a plurality of flexible spaced horizontal members secured to said vertical members, guide members secured to the ends of said vertical members slidably associated with said guides and a vertical bar slidably associated with said guides, the ends of said horizontal members being secured to said vertical bar and said car adjacent to and beyond the rear edge of said door opening, and means for tensioning said horizontal

members and fastening said door in closed position, said means comprising a plurality of hooked fingers engageable with said vertical bar.

10. In a stock car having an opening in a side thereof, guides secured to said car side adjacent opposed margins of said opening, a closure for said opening, said closure comprising a series of spaced, sturdy, vertical, flexible members, a series of spaced sturdy, horizontal, flexible members secured to said vertical members, devices secured to the ends of each of the members of one of said series slidably engaging said guides, means securing one end of each of the members of the other series to said car side adjacent said door opening, a bar secured to the opposite ends of the members of said other series and means secured to said car side adjacent to said opening for engaging said bar and fastening said closure across said opening.

11. In a stock car having an opening in a side thereof, guides secured to said car side adjacent opposed margins of said opening, a closure for said opening, said closure comprising a series of spaced sturdy vertical chains, a series of spaced sturdy horizontal chains, means slidably engaging said guides and secured to the chains of one of said series, means securing one end of the chains of the other of said series to said car adjacent said door opening and means for fastening the opposite end of the chains of said other series to said car when said closure extends across said opening.

12. A door for stock cars comprising a series of spaced vertical chains, a series of spaced horizontal chains extending between and secured to said vertical chains, a guide member secured to each end of each of the chains of one series and a bar secured to one end of each of the chains of the other series.

KENNETH J. TOBIN. 40
